COMBINATION HOSE-CLAMP PLIERS AND TUBE CUTTER

William Theodore Madeira, Lancaster, Pa., assignor to
K-D Manufacturing Company, Lancaster, Pa., a cor-
poration of Pennsylvania

Filed May 4, 1961, Ser. No. 65,023

Term of patent 14 years

(Cl. D54—13)

FIG. 1 is a front elevational view of a combination hose-clamp pliers and tube cutter showing my new design;

FIG. 2 is an elevational view taken from the left of FIG. 1 thereof;

FIG. 3 is an elevational view taken from the right of FIG. 1 thereof;

FIG. 4 is a rear elevational view thereof;

FIG. 5 is a top plan view; and

FIG. 6 is a bottom plan view thereof.

I claim:

The ornamental design for a combination hose-clamp pliers and the tube cutter, substantially as shown.
